UNITED STATES PATENT OFFICE.

GEORGE PARMITER, OF BUFFALO, NEW YORK, AND MICHAEL J. McDONNELL, OF HOLYOKE, MASSACHUSETTS.

DENTAL TOOL.

1,184,122.

Specification of Letters Patent. Patented May 23, 1916.

Application filed February 12, 1916. Serial No. 78,026.

To all whom it may concern:

Be it known that we, GEORGE PARMITER and MICHAEL J. McDONNELL, of Buffalo, county of Erie, State of New York, and Holyoke, county of Hampden, State of Massachusetts, respectively, with post-office address at 1396 Beacon street, Boston, Massachusetts, have invented an Improvement in Dental Tools, of which the following description, in connection with the accompanying drawings, is a specification, like characters on the drawings representing like parts.

This invention relates to dental tools, being intended to provide a simple but effective attachment for a dental engine adapted to impart a reciprocatory movement to a suitable device or implement such as a saw, abrasive or polishing strip or the like, for finishing and polishing fillings or separating and excising teeth, or any other purpose where such a reciprocatory movement is required.

The invention will be best understood by reference to the following description when taken in connection with the accompanying illustration of one specific embodiment thereof, while its scope will be more particularly pointed out in the appended claims.

In the drawings: Figure 1 is a side elevation of a tool embodying one form of the invention; Fig. 2 is a longitudinal, sectional elevation of the same; Fig. 3 is a plan view of the head piece which holds and guides the reciprocatory tool-carrying member; Fig. 4 is a plan of the tool shown in Fig. 2, looking from the underside with the head removed; and Fig. 5 is a similar plan with the tool carrier removed.

Referring to the drawings and to the embodiment of the invention therein shown, the same comprises a holder having the drum-shaped end 1 and the laterally extending neck 2. These and the other parts are shown on an exaggerated scale for the purpose of clearness. The end of the neck is threaded into the forward end of the sleeve 3, which latter is adapted to socket over the standard hand piece of any ordinary dental engine, serving as an intermediate connecting piece between the flexible shaft thereof and the tool holder.

Lateral driving movement is communicated from the shaft of the dental engine to

the tool through a suitable driving member, 55 herein consisting of the shaft or spindle 4, journaled in the neck 2 and having an end 5 projecting into the sleeve 3. The end 5 of the shaft has any suitable connection to the driving shaft of the engine, but preferably 60 one which is automatically made as the sleeve is slipped over the hand piece. At one end of the neck piece 2 the shaft 4 has the collar 6 pinned thereon and at the opposite end the small, beveled driving pinion 7 65 located within the drum 1 and meshing with a beveled gear 8, the latter arranged to turn within the drum upon the stud 9.

The cutting or abrasive device which is herein shown as a fine toothed saw blade 10, 70 but which may be of any suitable character, is shown as removably attached by suitable connections to the U-shaped tool holder 11, the back or connecting piece of the tool holder being in the form of a bar 12 shaped 75 to provide the right-angled slot 13 in which is seated the pin 14 projecting from the back of the beveled gear 8. The bar 12 of the tool holder is so guided that it may have reciprocatory movement across the axis of the 80 gear 8, the pin 14 and slot 13 providing a crank and slotted cross-head connection between the gear and the tool holder to convert the rotary movement of the driving shaft into a rapid reciprocatory movement 85 of the tool holder and its attached implement 10.

While the tool holder might be guided to move in a fixed, unchanging path, herein it is arranged to slide in slots 15—15 formed in 90 the rim 16 of a swiveled head piece 17, the latter being so attached to the drum 1 and holder 2 that it may be turned to a variety of different angles to secure the reciprocatory movement of the implement in the most 95 convenient direction for the work then being performed. The angular adjustment of the tool holder can be had quickly and readily without disconnecting the driving connections and leaving the latter as effective in 100 one position as another. Herein adjustment of the tool holder may be had through a range of approximately 300 degrees. To this end the swiveled head piece 17 is provided with diametrically opposite ears or 105 lugs 18 which project up over the outside of the drum 1 and overlie a circumferential groove 19 formed therein. These lugs carry

small pins or adjusting screws 20 which seat in the groove and by means of which the socket is held with the edges of the rim 16 in close abutting contact with the lower edges 5 of the drum 1, while at the same time permitting the socket piece to be turned to adjust the tool holder to different angular positions, as, for example, that indicated by dotted lines in Fig. 4.

10 While we have herein shown and described for purposes of illustration one specific form of the invention, it is to be understood that the same is not limited to the constructional details herein shown or to the 15 specific form or arrangement herein disclosed, but that extensive deviations may be made therefrom without departing from the spirit of the invention.

Claims:

20 1. A dental tool comprising a rotary drive member adapted for connection with a rotative shaft, a reciprocatory carrier for a tool or other implement, means for reciprocating said carrier through the rotation of said drive member, and a holder permitting the adjustment of said carrier to effect reciprocatory movement in a plurality of planes having different inclinations with relation to the axis of said driving member.

25 2. A dental tool having a holder, a rotary driving member adapted for connection with the rotative shaft of a dental engine, a reciprocatory carrier for the dental tool or other implement, a guide for said carrier swiveled on said holder and adapted to adjust said carrier to different angular positions of reciprocation, and means for reciprocating the carrier from 30 the rotary driving member in all the different angular positions of adjustment.

35 3. A dental tool comprising a holder, a sleeve secured thereto, a spindle having an end within the sleeve adapted for connection with the rotative shaft of a dental engine, said spindle extending into said holder, a beveled pinion on the end of the spindle, a beveled gear on the holder driven by said spindle, and a reciprocatory

50 tool-carrying member driven from said gear.

4. A dental tool comprising a holder, a sleeve secured thereto, a spindle having an end within the sleeve adapted for connection with the rotative shaft of a dental engine, said spindle extending into said holder, a beveled pinion on the end of the spindle, a beveled gear on the holder driven by said spindle, a reciprocatory tool-carrying member driven from said gear, and a 55 head piece guiding said carrier and swiveled on said holder whereby the carrier may be adjusted for angular positions of reciprocatory movement on the holder.

5. A dental tool comprising a holder, a sleeve secured thereto, a spindle having an end within the sleeve adapted for connection with the rotative shaft of a dental engine, said spindle extending into said holder, a reciprocatory tool carrying member, a head piece guiding said carrier and swiveled on said holder whereby the carrier may be adjusted for different angular positions of reciprocatory movement on the holder, said carrier having an arm provided 70 with a slot at right angles to the line of reciprocatory movement, a rotary member in the holder and having a pin working in said slot, and beveled gearing in the holder for driving the rotary member from said 75 spindle.

6. A dental tool comprising a holder, a tool carrier guided in said holder to have a straight line reciprocatory movement, along a straight, non-curvilinear path, a spindle adapted for connection to the rotative shaft of a dental engine, and driving connections between said spindle and said tool carrier to impart a reciprocatory movement to the latter in said straight path.

90 In testimony whereof, we have signed our names to this specification, in the presence of two subscribing witnesses.

GEORGE PARMITER.

MICHAEL J. McDONNELL.
